UNITED STATES PATENT OFFICE

WILLIAM T. SNYDER, OF SODUS, NEW YORK

GRAVITY HINGE

Application filed June 14, 1928. Serial No. 285,491.

This invention relates to an improved gravity hinge for use in association with swinging doors and similar closures, and it has more particular reference to a hinge which is frequently referred to as the gravity actuated self closing type.

Hinges of this class usually embody a pair of complementary leaves having customary pivot knuckles through which a pintle passes, the knuckle being swingable around the pin during the opening and closing movement of the door.

One leaf is provided with an anti-friction roller which is in rolling contact with a cam track, which may be either on the pintle pin or on one of the knuckles of the complementary leaf. It is obvious then, that as the door opens, it raises upwardly, under the action of the roller and cam and is automatically returned to closing position by this same means under the action of gravity.

The present improvement is characterized by an improved pintle pin having an integral enlargement formed with a cam surface or track, this enlargement having a retaining prong adjustably associated with the keeper seat in a complementary knuckle, in order to permit the pintle pin to be adjusted circumferentially to vary the inclination of the track with respect to the anti-friction roller and to thereby accurately regulate the action of gravity.

Another feature of the invention is the beveled anti-friction roller and mounting means therefor, which is such as to facilitate action of the roller and to thereby render the operation of the construction more dependable and efficient.

Referring to the drawings:—

Figure 1 is an elevational view of the gravity hinge constructed in accordance with the present invention showing the leaves spread apart.

Fig. 2 is a side elevation with the leaves swung together.

Fig. 3 is a section taken approximately upon the plane of the line 3—3 of Fig. 1.

Fig. 4 is an enlarged fragmentary detail

view showing the cam adjusting and retaining means, and

Fig. 5 is also an exaggerated fragmentary detail view, showing the anti-friction roller and its mounting.

Considering the parts by reference numerals, it will be observed that one leaf is designated by the numeral 6, and the complementary leaf by the numeral 7. The leaf 6 is provided with longitudinally spaced hinged knuckles 8 and 9 respectively, surrounding the cylindrical pintles 10. The remaining leaf is provided with an upper knuckle 11, and a lower knuckle 12. The knuckle 12 is of special construction.

For example, as shown in Fig. 4, it is provided at its upper edge with circumferentially spaced depressions forming keeper seats 13. Formed on the pintle 10 and located between the knuckles 9 and 12 is an integral enlargement or cam 14, whose upper edge is formed with an inclined track 15, with which the anti-friction roller is cooperable. The roller 16 is attached to the knuckle 9.

It will be noted from Fig. 4, that the cam is provided, on its lower edge with a retainer prong 17, receivable in one of the depressions 13, thus allowing the pintle to be adjusted to vary the inclination of the track with respect to the anti-friction roller. The roller, which has a bevelled periphery engaging the cam track, is attached by a bracket 18 to the pintle 9.

I propose to provide a special mounting for this roller, and invite attention to Fig. 5, wherein it will be seen that 19 designates the cylindrical portion of a journal pin having a square end portion 20 fitted into correspondingly shaped openings in the pintle 9, and lower end portion of the bracket 18. Mounted on this portion 19 is a bushing 21, which constitutes the hub for the bevelled roller 16. This arrangement is advantageous from the standpoint of assembly as well as freedom of operation.

From the foregoing description and drawings, it will be seen that I have evolved and produced a novel gravity hinge for doors and the like, which is exceptionally efficient

in performance and capable of fulfilling the requirements of an invention of this class in a positive and dependable manner. It is smooth and quiet in operation and is a mechanical achievement which is regarded as practical and commercially eligible, as a competitive structure in the art. The important distinction of the circumferentially adjustable cam track with respect to the anti-friction roller to vary the action of gravity is an important point to bear in mind, since it characterizes and distinguishes the invention.

Moreover the rotation of the roller produced by the novel mounting is a feature not to be overlooked. It is thought, however, by considering the description in connection with the drawings, a clear understanding of the construction, operation and advantages will be had. Therefore, a more lengthy description is regarded as unnecessary.

Having thus described my invention, what I claim as new is:—

1. In a hinge structure of the class described, a pair of complemental leaves provided with pivot knuckles, one of said knuckles being formed with a bearing opening, a bracket carried by said one knuckle and having an opening for cooperation with the first-named opening, a journal pin having flattened ends fitting into said openings, a bushing surrounding the pin, between the bracket and knuckle, and a roller mounted on said bushing, said roller having a beveled periphery, and a pintle pin extending through said knuckles and being provided with a cam track with which said roller is cooperable, one of said knuckles being provided with depressions forming keeper seats, and said cam having a depending projection forming a detent selectively receivable in said seats.

2. A device of the character described comprising a leaf, a pivot knuckle carried by said leaf having a plurality of depressions therein, a rotatably shiftable pintle extending through said knuckle, a cam mounted on said pintle and extending over the knuckle, a protuberance carried by said cam for selective insertion in one of the depressions in the knuckle for maintaining the pintle and cam in an adjusted position against rotary movement therein, and means mounted thereon for co-action with the cam for causing the last named means to gravitate to a normal position from which same has been moved.

In testimony whereof I affix my signature.
WILLIAM T. SNYDER.
